(57) **CLAIM**

The ornamental design for a medical test instrument, as shown and described.

DESCRIPTION

FIG. 1 is a front view of a first embodiment of a medical test instrument;

FIG. 2 is a rear view of the first embodiment;
FIG. 3 is a left side view of the first embodiment;
FIG. 4 is a right side view of the first embodiment;
FIG. 5 is a top view of the first embodiment;
FIG. 6 is a bottom view of the first embodiment;
FIG. 7 is a top, front, and left side perspective view of the first embodiment;
FIG. 8 is a top, front, and right side perspective view of the first embodiment;
FIG. 9 is a bottom, rear, and right side perspective view of the first embodiment;
FIG. 10 is a bottom, rear, and left side perspective view of the first embodiment;
FIG. 11 is a front view of the first embodiment showing a first image of the sequence of the first embodiment;
FIG. 12 is a front view of the first embodiment showing a second image of the sequence of the first embodiment;
FIG. 13 is a front view of the first embodiment showing a third image of the sequence of the first embodiment;
FIG. 14 is a front view of the first embodiment showing a fourth image of the sequence of the first embodiment;
FIG. 15 is a front view of the first embodiment showing a fifth image of the sequence of the first embodiment;
FIG. 16 is a front view of the first embodiment showing a sixth image of the sequence of the first embodiment;
FIG. 17 is a front view of a second embodiment of the medical test instrument showing a first image of the sequence of the second embodiment, of which the front, rear, left side, right side, top, bottom, and perspective views are identical to the first embodiment;
FIG. 18 is a front view showing a second image of the sequence of the second embodiment;
FIG. 19 is a front view showing a third image of the sequence of the second embodiment;
FIG. 20 is a front view showing a fourth image of the sequence of the second embodiment;
FIG. 21 is a front view showing a fifth image of the sequence of the second embodiment;
FIG. 22 is a front view showing a sixth image of the sequence of the second embodiment;
FIG. 23 is a front view of a third embodiment of the medical test instrument showing a first image of the sequence of the

(Continued)

FIG. 73 is a front view showing a second image of the sequence of the twelfth embodiment;

FIG. 74 is a front view showing a third image of the sequence of the twelfth embodiment;

FIG. 75 is a front view showing a fourth image of the sequence of the twelfth embodiment; and,

FIG. 76 is a front view showing a fifth image of the sequence of the twelfth embodiment.

The broken lines in the drawings depict portions of the medical test instrument form no part of the claimed design. In each embodiment, the appearance of the images transitions sequentially between the images shown in FIGS. 11-16, FIGS. 17-22, FIGS. 23-28, FIGS. 29-34, FIGS. 35-40, FIGS. 41-46, FIGS. 47-51, FIGS. 52-56, FIGS. 57-61, FIGS. 62-66, FIGS. 67-71, and FIGS. 72-76 respectively. The process or period in which one image transitions to another forms no part of the claimed design.

1 Claim, 13 Drawing Sheets
